UNITED STATES PATENT OFFICE.

JOHN S. YERGASON, OF BROOKLYN, NEW YORK.

PACKAGE.

1,263,185.

Specification of Letters Patent. Patented Apr. 16, 1918.

Application filed June 2, 1917. Serial No. 172,370.

To all whom it may concern:

Be it known that I, JOHN S. YERGASON, a citizen of the United States, and a resident of the city of New York, borough of Brooklyn, in the county of Kings and State of New York, have invented a new and Improved Package, of which the following is a full, clear, and exact description.

The invention relates to packages containing folded pieces of textile material of delicate texture such as diaphanous fabrics of silk, cotton, silk and cotton, and the like.

The object of the invention is to provide a new and improved package arranged to hold the folded piece without producing a longitudinal crease therein and to protect the folded piece against dust or being soiled while handled, shipped or stored. Another object is to enable the user to unpack the folded piece and unfold the same in open width and in perfectly flat condition on a cutting table without producing the undesirable and objectionable crease running lengthwise from one end of the piece to the other, thus enabling the cutter to advantageously place the pattern in position with a view to accurately cut up the material without requiring stretching thereof and without requiring extra help. Another object is to enable the manufacturer of the goods to dispense with the reeling of the piece after it leaves the finishing machine, thus saving considerable expense prior to packaging the piece. A further object is to dispense with the tying tapes now generally used, and still another object is to safeguard the package against being tampered with by unauthorized persons while in transit.

In order to accomplish the desired result, use is made of a slit package comprising a body of sheet material adapted to contain a folded piece of textile material, the said body being of a length corresponding approximately to the width of the folded piece, and the body with the folded piece therein being doubled up and forming overlying members, and locking means connecting the free sides of the overlying members with each other. Use is also made of a wrapper contained within the said body and inclosing the folded piece of textile material, the said wrapper being slit within the body and the latter being slit exteriorly.

A practical embodiment of the invention is represented in the accompanying draw-

ings forming a part of this specification, in which similar characters of reference indicate corresponding parts in all the views.

Figure 1 is a perspective view of the 60 locked and slit package containing a folded piece of textile material;

Fig. 2 is a cross section of the same on the line 2—2 of Fig. 1;

Fig. 3 is a reduced plan view of the pack- 65 age in open position and without the folded piece of textile material;

Fig. 4 is an inverted plan view of the same;

Fig. 5 is a cross section of the same on the 70 line 5—5 of Fig. 3 and with the folded piece of textile material in position;

Fig. 6 is a plan view of the same partly folded; and

Fig. 7 is a longitudinal central section of 75 the folded and slit package, with the piece of textile material contained therein.

The improved package is adapted to contain a folded piece 10 of textile material, preferably of the type above referred to, 80 and it consists essentially of a wrapper 11 of the usual thin wrapping paper or tissue paper, and an outer body or shell 12 of a sheet of strong paper or thin cardboard, to permit of doubling it up with a 85 view to form a bottom member 13 and a top member 14. The sides of the members 13 and 14 are provided with inwardly extending closing flaps 15 and 16, and the bottom member 13 is provided at its ends with 90 end flaps 17 and 18 for closing the ends of the package. The bottom member 13 is provided with a locking tongue 20, preferably cut out of the side flap 15, and this locking tongue 20 is adapted to engage slits 95

21 formed in the top member 14 to securely lock the members 13 and 14 together at their free sides. The end flaps 17 and 18 are provided with locking tongues 22, 23 (see Figs. 1 and 4) to engage longitudinal slits 100

24, 25 formed on the top member 14 to securely lock the end flaps 17 and 18 in position. A seal 26 is preferably attached, partly to the locking tongue 20 and the member 14, and similar seals 27 and 28 engage the tongues 22 and 23 and the top member 14, to prevent tampering with the package by unauthorized persons. In order to render the ends of the package dustproof, use is made of end flaps 40, 41 and 42, of 110 which the flaps 40 are integral on the top member 14 and the flaps 41 and 42 are in-

tegral on the side flaps 15 and 16 and the said flaps 40, 41 and 42 are bent inward prior to folding the end flaps 17 and 18 onto the top member 14. The inner wrapper 5 per 11 is of a length exceeding the length of the body 12 and is provided with inwardly extending side flaps 30 and 31 folded over the top of the folded piece 10 of textile material, as plainly indicated in Fig. 5. 10 The projecting portions 32 and 33 of the inner wrapper 11 are provided at their outer edges and at the median center line of the said wrapper with gummed seals 34, 35, to provide an inner seal for this wrapper 15 11, as hereinafter more fully explained. In order to inclose the folded piece 10 of textile material, the body 12 with the wrapper 11 superimposed thereon is spread open; as indicated in Fig. 3, and the folded piece 20 10 is then placed on top of the wrapper 11 with the folds tucked under the side flaps 30 and 31, as plainly indicated in Fig. 5. The body 12 is now doubled up and the tongue 20 is interlocked with the slits 21, 25 after which the projecting ends 32 and 33 of the wrapper 11 are folded up sidewise, as indicated in Fig. 6, and tucked under the top member 14 of the body 12. Prior to tucking under the projecting ends 32 and 30 33 the seals 34 and 35 are moistened, and after the said projecting ends 32 and 33 have been tucked under a pressure is exerted on the top member 14 opposite the seals 34, 35 to cause the latter to firmly 35 adhere to the top of the upper portion of the inner wrapper 11, thus sealing the latter within the body 12. The flaps 40, 41 and 42 are now folded inward and then the end flaps 17 and 18 are folded over the ends 40 of the package and onto the top member 14 of the body 12, after which the locking tongues 22 and 23 are engaged with the slits 25, as plainly shown in Fig. 1, and then the seals 26, 27 and 28 are applied to seal the 45 locking tongues 20, 22 and 23 against surreptitious opening. It will be noticed that by the arrangement described, the folded piece of textile material 10 is securely inclosed within the inner wrapper 11, and the 50 latter with the folded piece 10 therein is safely housed within the locked and slit body 12 and in such a manner that a longitudinal creasing of the folded piece is entirely prevented. 55 From the foregoing it will be seen that the manufacturer can dispense entirely with the reeling of the piece of textile material, the ends only being folded in the usual manner. The folded piece of textile material is then inclosed in the wrapper 11 contained with the body 12 of the package and with the inner wrapper sealed interiorly and the outer body 12 sealed exteriorly. The package can be safely shipped by the

manufacturer to its distributor and finally to the customer, and during the transportation and possible storing of the package the folded piece of textile material is not liable to be soiled or otherwise injured by dust or handling. 70

It will also be noticed that during transportation unauthorized persons cannot without detection abstract the material or a portion thereof as it would be necessary to break the inner and the outer seals above 75 mentioned. 75

The user when unpacking the textile material breaks the seals, opens up the package and removes the folded piece of textile material to a cutting table on which the textile material is unfolded. In practice, a number of such pieces are superimposed on the cutting table, and when the desired pile has been made, the patterns are placed on the uppermost piece to enable the operator 80 to cut the superimposed pieces according to the patterns. 85

It will be noticed that by having no longitudinal creases on each of the pieces the latter lie flat, one on top of the other, and the patterns can be very advantageously placed on account of being unhampered by a ridge which has been formed by the longitudinal creases. It will also be noticed that no sidewise stretching of the pieces on the 90 cutting table is required owing to the absence of creases, and hence a single person can properly place the several pieces one on top of the other without the aid of another person. 100

Having thus described my invention, I claim as new and desire to secure by Letters Patent:—

1. In a package containing a folded piece of textile material, a body of sheet material 105 inclosing the folded piece, said body being doubled up and forming two overlying members provided at the sides with flaps extending within the folds of said folded piece, one of the members being provided with end 110 flaps extending over the ends of the package onto the other member and fastened thereto, one of the said members having a locking flap on one side engaging the other member. 115

2. In a package containing a folded piece 120 of textile material, a body of sheet material inclosing the folded piece, said body being doubled up and forming two overlying members provided at the sides with flaps extending within the folds of said folded piece and 125 provided with small end flaps, one of the members being provided with small end flaps, and the other member with large end flaps, said large end flaps extending over the ends of the package and the small end flaps onto the first member and having interlocking engagement therewith, the side flap of one member being provided inter- 125

mediate of its ends with an integral tongue having interlocking engagement with the other member.

3. In a sealed package containing a folded piece of textile material, an inner wrapper for the folded piece having end flaps adapted to be tucked under, an outer wrapper of sheet material inclosing the inner wrapper and the folded piece contained therein, the 10 said outer wrapper being of a length corresponding approximately to the width of the folded piece and being doubled up forming two overlying members provided at the sides with flaps extending within the folds 15 of said folded piece, one of the members being provided with end flaps extending over the ends of the package and onto the other member, locking and sealing means for the said end flaps, a tongue cut from the flap 20 of one member intermediate of its ends and extending over the other member, locking

and sealing means for said tongue, and inner sealing means for the said tucked under end flaps of the inner wrapper.

4. A package wrapper, consisting of a 25 sheet of pliable material doubled up and forming two members provided with inwardly extending side flaps, each having small end flaps, one of the members being provided with small end flaps, and the other 30 member with large end flaps extending over the said small end flaps and having interlocking engagement with the first member, the side flap of one member being provided at about its center of length with a tongue 35 cut therefrom, said tongue extending outside of the inwardly projecting portion of the flap and extending over the other member and having interlocking engagement therewith.

JOHN S. YERGASON.
